UNITED STATES PATENT OFFICE

157,933

LIQUID DISPENSER FOR HAND LOTION OR THE LIKE

Joseph F. M. Ball, Youngstown, Ohio

Application December 5, 1947, Serial No. 142,965

Term of patent 3½ years

(Cl. D52—3)

To all whom it may concern:

Be it known that I, Joseph F. M. Ball, a citizen of the United States, residing at Youngstown, in the county of Mahoning and State of Ohio, have invented a new, original, and ornamental Design for a Liquid Dispenser for Hand Lotion or the like, of which the following is a specification, reference being had to the accompanying drawing, forming a part thereof.

Figure 1 is a top plan view of a liquid dispenser for hand lotion or the like, showing my new design.

The left side of the liquid dispenser is substantially a duplicate of the right side thereof.

I claim:

The ornamental design for a liquid dispenser for hand lotion or the like, as shown and described.

JOSEPH F. M. BALL.
